UNITED STATES PATENT OFFICE

GASTON BROWN KILLAM, OF DENVER, COLORADO, ASSIGNEE TO KILLAM GAS BURNER COMPANY, OF DENVER, COLORADO, A CORPORATION OF COLORADO

GAS BURNER

Application filed May 28, 1930. Serial No. 456,511.

This invention relates to improvements in gas burners of the type employed for heating purposes and which are especially adapted for use with natural gas.

5 It is the object of this invention to produce a gas burner of a simple construction that shall be especially well adapted for use with natural gas for heating buildings and which shall be so designed that it can be readily 10 employed for converting ordinary coal burning furnaces and heaters into gas burning furnaces and heaters.

It is another object of this invention to produce a burner of such construction that 15 the gas shall be thoroughly mixed with air in such quantities that a complete combustion takes place, and therefore there will be no soot and a high thermal efficiency will be obtained.

20 Another object of this invention is to produce a gas burner that shall be provided with means for supplying auxiliary air that has previously been heated to a high temperature and mixing it with the flame so 25 that there will always be a slight excess of oxygen thereby assuring that all the heat units in the gas will be converted into heat.

This invention, briefly described, consists 30 of a vertical tubular member whose upper end is open and whose lower end is provided with an adjustable closure. Surrounding the tubular member adjacent its upper end is a circular wall whose lower end is connected with the tubular member so as to form an 35 annular chamber. A gas pipe is connected with this chamber and supplies a mixture of air and gas which escapes through the open end of the chamber. A frusto conical deflector plate is secured to the tubular member 40 and located directly above the annular chamber. The lower surface of the deflector is spaced a short distance from the upper end of the cylindrical wall that forms the outer surface of the chamber so as to leave an 45 annular space through which the gas may escape. A frusto-conical member is located 50 above the deflector and supported by the latter but spaced a short distance from it. The center of this frusto-conical member is provided with an opening that is larger than

the outside diameter of the tubular member and the latter projects into the frusto-conical member whose upper end is closed by means of a cover. Air passing upwardly through the tubular member becomes highly heated in 55 the chamber of the frusto-conical member and finally escapes through the space between this member and the frusto-conical deflector. Means is provided for introducing a mixture of gas and air into the gas pipe. 60

Having thus briefly described the invention, the same will now be described in detail, and for this purpose reference will be had to the accompanying drawing in which the preferred embodiment of the invention 65 has been illustrated, and in which:

Fig. 1 shows a side elevation of the improved burner, portions thereof being shown in section to better disclose the construction. 70

Fig. 2 is a plan view looking down upon 75 the refractory spreader, that is supported on the burner, this view being taken looking in the direction of arrow 2 in Fig. 1;

Fig. 3 is a section taken on line 3—3, Fig. 75; and

Fig. 4 is a section taken on line 4—4, Fig. 3.

In the drawing reference numeral 1 represents the floor on which the furnace is supported and 2 the walls of the combustion chamber, while 3 indicates the ashbox. Located within the combustion chamber is the improved burner which consists of a vertically tubular member 4, whose lower end is connected with an elbow 5. This elbow is supported from a base 6 by means of a short 80 piece of pipe 7. A pipe 8 extends outwardly from the elbow and terminates in a fitting 9 that is provided with a movable cover 10. This cover can be moved from the position shown in Fig. 1 so as to close the opening in pipe 8 and can therefore be used for controlling the flow of air through the tubular member. Surrounding the tubular member near its upper end is a cylindrical wall 11 whose lower end is connected with the tubular member as indicated at 12. The inner surface of wall 11 is spaced from the outer surface of the tubular member and forms an annular chamber 13, to the bottom of which the gas pipe 14 is connected. A frusto-conical de- 85

reflector 15 is supported by the tubular member a short distance above the upper end of wall 11 and serves to deflect the gas outwardly. A frusto-conical member 16 is supported by the deflector 15 and spaced from the latter by means of spacers 17. Member 16 is provided with a central opening 18 through which the tubular member 4 extends. The upper end of the frusto-conical member is provided with a cover or closure 19, which in turn has an upwardly extending centrally located extension 20 that has an enlarged head 21. Spreader members 22 of refractory materials are supported on the upper surface of the cover and have portions projecting under the head 21 in the manner shown in Fig. 1. The lower end of gas pipe 14 is connected with an elbow 23 from which a pipe 24 extends outwardly and connects with the inner end 25 of the mixing device which will now be described. Pipe 24 constitutes part of the burner nozzle and terminates in an annular chamber 13. The mixing device consists of the part 25 to which reference has already been made and which is provided with an outwardly extending flange 26 to which the circular sleeve 27 is attached. A funnel-shaped member having a tubular portion 28 and an outwardly flared frusto-conical portion 29 is preferably formed integral with member 25, and is connected to and spaced from the latter by means of ribs 30. The outer end of member 29 has a diametrically extending rib 31 whose center portion is provided with an enlarged part 32 whose inner end has a small opening 33. A gas pipe 34 is connected with the open end of part 32 in the manner shown in Fig. 4. The outer end of cylindrical member 27 is closed by means of a plate 35 that has a plurality of sector-shaped openings 36. A movable plate 37 is rotatably mounted on the pipe 34 and held in position against plate 35 by means of a nut or collar 38. This plate has openings 36a that are of the same size and shape as the openings 36 in plate 35. When plate 37 is in the position shown in Fig. 3, the openings 36 and 36a register and therefore provide passage through which air may enter. Plate 37 is provided on one side with an arm 39 to the outer end of which a wire or cable 40 is secured. This cable extends upwardly and is connected with the operating lever 41 of the gas controlled valve which will be referred to hereinafter. Cylindrical member 27 is provided on one side with an opening 42 and this opening can be closed by means of a cover 43 that is hinged at its upper end as indicated at 44. This cover is provided with a pin 45 that extends outwardly from one side thereof, and which is adapted to be engaged by the cam surface 46 of arm 39. When plate 37 is rotated in the direction of the arrow in Fig. 3, the cam surface 46 comes into contact with pin 45 and opens the cover 43 so as to permit

air to enter through opening 42. A wire 47 connects the operating lever 41 with the closure 10 so that when lever 41 moves upwardly into the position shown in Fig. 1, it opens the covers 10 and 43 and also rotates plate 37 into such position that the openings 36 and 36a register. A chain or wire 48 connects the outer end of lever 41 with a thermostatically controlled mechanism that turns the gas on and off at predetermined temperatures. A weight 49 tends to move the lever 41 downwardly and a similar weight 50 tends to rotate plate 37 in a counter-clockwise direction. The automatic gas valve has been designated as an entirety by reference numeral 51 and is shown in Fig. 1 in open position. When the tension on wire 48 is released, weight 49 will move lever 41 downwardly, thereby moving the valve part upwardly until the spring 52 passes through the dead center position and moves the valve to closed position by a snap action, and at the same time closes openings 36 and moves the covers 10 and 43 to closed position. A pilot burner which has not been shown is usually provided for the purpose of igniting the gas when the control valve is again moved to open position.

When the control valve is in open position gas flows through pipe 34 into the interior of the nozzle 32 and emerges at high velocity through opening 33. This produces a suction that causes primary air to flow inwardly through openings 36 as indicated by arrow 53. This air mixes with the gas and the mixture of gas and air then flows through the tubular nozzle 28 and emerges from this at a high velocity, thereby producing suction that draws auxiliary primary air inwardly through opening 42 in the direction of arrow 54. This air will be referred to as the auxiliary primary air and by properly proportioning the primary and auxiliary primary air, an ideal combustion can be obtained. This mixture of gas and air flows through pipes 24 and 14 into chamber 13 and emerges through the annular space between the wall of this chamber and the deflector 15 which spreads the flame outwardly against the inner wall of the combustion chamber. The flow of gas upwardly along plate 15 produces an area of low pressure between the edge of the deflector and the outer surface of frusto-conical member 16 and thereby induces secondary air to flow upwardly through the tubular member into the chamber in member 16 and thence downwardly and out through the space between the deflector and frusto-conical member 16. This secondary air develops the flame and is highly heated due to the fact that it passes slowly through the chamber within member 16. The heated secondary air combines readily with the combustible carbon particles of the gas with the result that the combustion is very complete and therefore a high thermal efficiency ob-

tained. When the secondary air comes into contact with the flame, a blast like effect is produced and the temperature of the flame is greatly increased.

5 In the embodiment illustrated in the drawing and specifically described herein the passage for the secondary air is formed by placing member 16 with its lower end inside of member 15 and spacing the adjacent surfaces 10 by means of lugs 17. The amount of the overlap is immaterial and this is merely an example showing one way in which the opening for the air can be formed. It is also obvious that member 16 also serves as a deflector or spreader and that it in effect forms a continuation of surface 15.

From the above description it will be seen that I have produced a burner of a simple construction that is especially well adapted 20 for use in connection with furnaces and other heaters and which is so constructed that air is supplied at three different places, thereby producing a thorough mixture of gas and air and at the same time supplying a large quantity 25 of secondary air that has been highly preheated, whereby a high thermal efficiency is obtained.

Having described the invention what is claimed as new is:

30 1. A gas burner comprising a central tubular member having one end open and the other provided with a movable closure, a wall surrounding the tubular member adjacent its open end and spaced therefrom, the end 35 of the wall farthest from the open end being attached to the tubular member whereby an annular chamber is formed, a gas pipe in communication with the annular chamber, a frusto-conical deflector surrounding the 40 tubular member at a point above the wall and spaced from the top of the latter whereby an annular opening is formed for the escape of gas, a frusto-conical member supported above the frusto-conical deflector and 45 spaced from the latter, the frusto-conical member having a central opening that is larger than the outside of the tubular member and a cover for closing the upper end of the frusto-conical member whereby a chamber 50 is formed about the open end of the tubular member, which serves as a preheating chamber for secondary air that enters through the tubular member and escapes through the opening between the frusto-conical deflector 55 and the frusto-conical member, means for supplying a mixture of air and gas to the gas pipe, means for controlling the air and gas mixture, a regulator for controlling the flow of air through the tubular member and means for simultaneously varying the air and gas mixture and the amount of air that flows through the tubular member.

2. A gas burner comprising a central tubular member having one end open and the other provided with a movable closure, a wall surrounding the tubular member adjacent its open end and spaced therefrom, the end of the wall farthest from the open end being attached to the tubular member whereby an annular chamber is formed, a gas pipe 60 in communication with the annular chamber,

a frusto-conical deflector surrounding the tubular member at a point above the wall and spaced from the top of the latter whereby an annular opening is formed for the escape of gas, a frusto-conical member supported 70 above the frusto-conical deflector and spaced from the latter, the frusto-conical member having a central opening that is larger than the outside of the tubular member, a cover for closing the upper end of the frusto-conical member whereby a chamber is formed about the open end of the tubular member which serves as a preheating chamber for auxiliary air that enters through the tubular member and escapes through the opening 75 between the frusto-conical deflector and the frusto-conical member and means for controlling the flow of air through the tubular member.

3. A gas burner comprising a central tubular member having one end open and the other provided with a movable closure, a wall surrounding the tubular member adjacent its open end and spaced therefrom, the end of the wall farthest from the open end being 80 attached to the tubular member whereby an annular chamber is formed, a gas pipe in communication with the annular chamber, a frusto-conical deflector surrounding the tubular member at a point above the wall 85 and spaced from the top of the latter whereby an annular opening is formed for the escape of gas, a frusto-conical member supported above the frusto-conical deflector and spaced from the latter, the frusto-conical member having a central opening that is larger than the outside of the tubular member, a cover for closing the upper end of the frusto-conical member whereby a chamber 90 is formed about the open end of the tubular member, which serves as a preheating chamber for secondary air that enters through the tubular member and escapes through the opening between the frusto-conical deflector and the frusto-conical member, means for 95 supplying a mixture of air and gas to the gas pipe, means for controlling the air and gas mixture, a regulator for controlling the flow of air through the tubular member and means for simultaneously varying the air and gas mixture and the amount of air that flows through the tubular member.

4. A gas burner comprising an open ended tubular member provided with an annular chamber about its outer surface and adjacent the open end, the chamber being open at the end adjacent the open end of the tubular member and closed at the other end, a gas pipe in communication with the chamber, means for supporting the tubular member in vertical position with its open end uppermost, the lower end of the tubular member having a movable closure, a frusto-conical deflector surrounding the tubular member 100 between the annular chamber and the upper 105 end of the tubular member, a gas pipe in communication with the annular chamber, a cover for closing the upper end of the tubular member, a frusto-conical deflector surrounding the tubular member 110 between the annular chamber and the upper end of the tubular member, a gas pipe in communication with the annular chamber, a cover for closing the upper end of the tubular member, a frusto-conical deflector surrounding the tubular member 115 between the annular chamber and the upper end of the tubular member, a gas pipe in communication with the annular chamber, a cover for closing the upper end of the tubular member, a frusto-conical deflector surrounding the tubular member 120 between the annular chamber and the upper end of the tubular member, a gas pipe in communication with the annular chamber, a cover for closing the upper end of the tubular member, a frusto-conical deflector surrounding the tubular member 125 between the annular chamber and the upper end of the tubular member, a gas pipe in communication with the annular chamber, a cover for closing the upper end of the tubular member, a frusto-conical deflector surrounding the tubular member 130 between the annular chamber and the upper end of the tubular member.

end of the tubular member, the lower surface of the deflector being spaced a short distance from the upper edge of the wall of the chamber whereby an annular opening is produced for the escape of a combustible mixture of gas and air, a frusto-conical member located above the deflector and having its under surface spaced from the upper surface of the deflector, the frusto-conical member having a central opening somewhat larger in diameter than the outside diameter of the tubular member, a cover for closing the upper end of the frusto-conical member whereby a chamber is formed for preheating air and means for delivering a mixture of air and gas to the first mentioned chamber.

5. A gas burner comprising an open ended tubular member provided with an annular chamber about its outer surface and adjacent the open end, the chamber being open at the end adjacent the open end of the tubular member and closed at the other end, a gas pipe in communication with the chamber, means for supporting the tubular member in vertical position with its open end uppermost, the lower end of the tubular member having a movable closure, a frusto-conical deflector surrounding the tubular member between the annular chamber and the upper end of the tubular member, the lower surface of the deflector being spaced a short distance from the upper edge of the wall of the chamber whereby an annular opening is produced for the escape of a combustible mixture of gas and air, a frusto-conical member located above the deflector and having its under surface spaced from the upper surface of the deflector, the frusto-conical member having a central opening somewhat larger in diameter than the outside diameter of the tubular member, a cover for closing the upper end of the frusto-conical member whereby a chamber is formed for preheating air, means for delivering a mixture of air and gas to the first mentioned chamber and means for simultaneously varying the gas and air mixture and the amount of air that flows through the tubular member.

6. A gas burner comprising a central tubular member having one end open and the other provided with a movable closure, a wall surrounding the tubular member adjacent its open end and spaced therefrom, the end of the wall farthest from the open end being attached to the tubular member whereby an annular chamber is formed, a gas pipe in communication with the annular chamber, a deflector having a substantially frusto-conical surface surrounding the tubular member at a point above the wall and spaced from the top of the latter whereby an annular opening is formed for the escape of gas, and a closure for the upper end of the deflector, the wall of the deflector having a passage

through which secondary air may pass to the interior of the escaping gas.

7. A gas burner comprising an open ended tubular member provided with an annular chamber about its outer surface and adjacent the open end, the chamber being open at the end adjacent the open end of the tubular member and closed at the other end, a gas pipe in communication with the chamber, means for supporting the tubular member in vertical position with its open end uppermost, the lower end of the tubular member having a movable closure, a deflector having a substantially frusto-conical surface surrounding the tubular member between the annular chamber and the upper end of the tubular member, the lower surface of the deflector being spaced a short distance from the upper edge of the wall of the chamber whereby an annular opening is produced for the escape of a combustible mixture of gas and air and a closure for the upper end of the deflector whereby a heating chamber is formed for heating secondary air, there being a passage-way through said surface for the heated air to pass from the heating chamber to the inside of the escaping air and gas mixture.

8. A gas burner comprising an open ended tubular member provided with an annular chamber about its outer surface and adjacent the open end, the chamber being open at the end adjacent the open end of the tubular member and closed at the other end, a gas pipe in communication with the chamber, means for supporting the tubular member in vertical position with its open end uppermost, the lower end of the tubular member having a movable closure, a deflector having a substantially frusto-conical surface surrounding the tubular member between the annular chamber and the upper end of the tubular member, the lower surface of the deflector being spaced a short distance from the upper edge of the wall of the chamber whereby an annular opening is produced for the escape of a combustible mixture of gas and air, a closure for the upper end of the deflector whereby a heating chamber is formed for heating secondary air, there being a passage-way through said surface for the heated air to pass from the heating chamber to the inside of the escaping air and gas mixture, the upper surface of the closure having a central upwardly projecting lug whose upper end has an outwardly extending flange and refractory deflector members supported on the closure and having portions extending underneath the flange to hold them in place.

In testimony whereof I affix my signature.
GASTON BROWN KILLAM.
